UNITED STATES PATENT OFFICE.

THOMAS H. GASKIN, OF WOODFORD, ENGLAND.

REVERSIBLE BOAT.

1,408,580.

Specification of Letters Patent. Patented Mar. 7, 1922.

Application filed July 24, 1919. Serial No. 312,935.

To all whom it may concern:

Be it known that I, THOMAS H. GASKIN, a subject of the King of Great Britain, and a resident of Woodford, county of Essex, 5 England, have invented certain new and useful Improvements in Reversible Boats, of which the following is a specification.

This invention relates to improvements in reversible boats adapted for being carried on ship board and capable of use as life boats with which ships are as a rule provided. Such a boat comprises a buoyancy chamber extending around the periphery thereof and means placed about midway 10 of the boat as a whole for dividing the boat into substantially symmetrical upper and lower portions, either one of which when turned uppermost, provides a well fitted with thwarts and other necessary devices 15 capable of serving for the accommodation of passengers.

The means hereinafter referred to as the deck of the boat which divides the boat into upper and lower portions, is provided 20 with passageways extending through the same, each of which passageway is furnished with a valve provided with means serving at all times to automatically maintain the valve closed. One of the valves, 25 when the boat is afloat, serves to permit the escape of air from beneath the boat which would otherwise be confined under pressure within the well of what is then the inverted half of the boat and the other valve serves 30 to permit the escape of water from the well of the upper half of the boat, at the same time, however, preventing water surging through the passageway in the deck and entering the well of the upper half of the 35 boat.

Preferrably these passageways in the deck, of which there are at least two, are provided with vent tubes which extend in opposite directions from the deck, each tube 40 being of sufficient length to reach well above the level of the water upon which the boat is resting when afloat.

As a result of this construction it is obvious that either compartment or well of 45 the boat serves for the reception of passengers, likewise that both wells are self-bailing, and as a whole the boat will be very stable.

In the accompanying drawings wherein I 50 have illustrated an embodiment of my invention,

Fig. 1 shows in perspective my improved reversible boat;

Fig. 2 is a transverse section taken about midway of the length of the boat; and 60

Fig. 3 is a view similar to Fig. 2 with the valve mechanism shown very much enlarged.

Referring to the drawings in detail, 1 designates the boat in general which as disclosed in section in Figs. 2 and 3, is provided with a buoyancy chamber 2 extending around its periphery. About midway of the depth of the boat I have provided a dividing means or deck dividing the boat into two 10 substantially symmetrical upper and lower halves 5 and 6. As illustrated the deck comprises two spaced apart partitions 3 and 4 and a buoyancy chamber 7 between the same, which obviously increases the buoyancy of 15 the boat and therefore its passenger-carrying capacity, but it is to be understood that it is within the scope of the present invention to provide but a single deck if desired. 20

Extending through the deck members 3 and 4 are passageways 8 and 9 which as illustrated, are provided with vent tubes 10 and 11 respectively. It may here be mentioned that while I have illustrated but two 25 vent tubes the number may be increased as desired. The vent tube 10, assuming for example, that the boat is in the water, extends upwardly from the deck of the boat to a point above the level of the water upon 30 which the boat is resting, while the lower end of this tube is substantially flush with the surface of the under side of the deck member 4. The tube 11 is a duplicate, substantially, of the tube 10, this tube, however, in the assumed position of the boat, extending downwardly from the deck member 3, substantially the same distance that the tube 10 extends above the surface of the deck number 4. The tube 10 is provided 35 with a valve 12 and the tube 11 with a valve 13, the valve 12 in the position shown in Fig. 2 opening upwardly while the valve 13 in the same figure opens downwardly. As these valves are duplicates of each other, 40 so far as their construction is concerned, a description of one will suffice for both.

Referring to the enlarged view (Fig. 3) it will be seen that the valve 13 comprises a valve plate 14 pivoted at 15 and having 45 a rearwardly extending weighted portion 16 sufficiently heavy to cause the valve plate

to be swung to closed position when the boat is in the position shown in Fig. 2, but the valve plate is so balanced that any water entering the well 5 will force the 5 valve open against the action of the weighted portion 16 to permit the water to escape through the passageway 9 and into the well 6 which, it will be understood, is not quite entirely submerged in the water upon which 10 the boat is resting. Secured to the side of the tube in any suitable manner, is a bell-crank-lever provided with arms 17 and 18 pivoted at 19, the arm 17 being weighted. With the tube 11 in the position assumed, 15 it will be obvious that the weighted arm 17 will drop to cause the bell-crank-lever to rock about its pivot to carry the arm 18 out of the path of the valve 14 so that the latter is free to move to open position under 20 the action of any water in the well 5 so far as the bell-crank-lever is concerned. Of course it will be understood that in the tube 10 at this time, the valve mechanism will be reversed, that is to say, the tendency of the 25 valve plate 14 in that tube is to lift off its seat due to the action of the weight 16, but this movement of the valve is prevented by reason of the fact that the weighted arm 17 will have moved about its pivot to cause 30 the end of the arm 18 to be immediately above the end of the valve plate to prevent the same from lifting off its seat to any considerable extent, a small amount of play, however, designated by reference character 35 20, being provided between the end of the arm 18 and the valve plate.

Assuming now that the boat is in the water with the well 5 uppermost, the weighted arm 17 in the tube 11 will fall to 40 cause the arm 18 of the bell-crank-lever to move away from beneath the valve plate 14, and any water contained within the well 5 is free to open the valve against the action of the weighted portion 16 thereof and 45 escape beneath the boat, the valve immediately returning to its closed position so that water surging upwardly beneath the boat may not enter the well 5. At this time also, the valve in the tube 10 is maintained 50 in substantially closed position, due to the arm 17 having, under the action of gravity, been swung around to carry the end of the arm 18 beneath the valve 14 but it will be noticed that air confined in the well 6 beneath 55 the deck of the boat is free to escape to the atmosphere by reason of the clearance 20 which has been provided between the surface of the valve and the end of the arm 18.

60 As before pointed out, the vent tubes 10 and 11 prevent compression of air beneath the deck of the boat when the boat is in the water which would cause the boat to be

more or less unstable and also insure that the boat will be self-bailing and therefore 65 the well 5 or 6 as the case may be, whichever happens to be uppermost, will be maintained in a dry condition.

While the valves 12 and 13 have been illustrated as being located at the deck end 70 of the vent tubes, it is understood that I am not to be confined to this location of the valves for obviously the same may be located at the outer end of the tubes if desired. It is further understood that I am not to be 75 limited to the precise construction illustrated of the automatic means for maintaining the valves closed as obviously this construction might be varied by others skilled in the art without departing from the spirit 80 and scope of this invention.

I believe that I am the first to provide vent tubes and valve mechanism for the purpose of rendering a boat self-bailing and to prevent compression of air beneath the 85 deck of the same wherein the valves are automatically maintained in substantially closed position at all times.

What I claim as new is:

1. In a reversible boat, the combination of 90 means for dividing the boat into substantially symmetrical upper and lower portions said means being provided with passageways extending therethrough, vent tubes extending in opposite directions from said 95 passageways, one of said tubes communicating with one compartment and the other tube with the other compartment, oppositely disposed pivoted valves in said vent tubes for controlling said passageways, said valves 100 being so pivoted that the valve in the vent tube which extends downwardly will remain closed when the compartment with which this tube is in communication is free of water, and the other valve in the other tube 105 will be maintained in partially open position.

2. In a reversible boat, the combination of 110 means for dividing a boat into two substantially symmetrical upper and lower portions, vent tubes extending through said dividing means in opposite directions, a weighted pivoted valve in each of said vent tubes, and a bell-crank-lever in each of said 115 vent tubes co-operating with each of said valves for preventing the full opening of a valve when a vent tube is in one position and automatically moving said valve to closed position when the vent tube is moved to another position.

This specification signed and witnessed 120 this 18th day of July, A. D., 1919.

THOMAS H. GASKIN.
